AUTOMATIC REPLENISHING LOOM

Carl D. Brown, Hopedale, Mass., assignor to
Draper Corporation, Hopedale, Mass., a corpo-
ration of Maine

Application June 5, 1940, Serial No. 338,973

11 Claims. (Cl. 139—256)

The present invention pertains to automatic filling replenishing looms having pneumatic means for holding and tensioning the filling thread and removing loose pieces of filling ends 5 from the loom, and more particularly relates to the actuating and controlling of such means.

The usual automatic filling replenishing loom includes a reciprocating lay, a shuttle, and filling replenishing mechanism including a magazine for holding a multiplicity of reserve filling carriers. The ends of the filling thread on the reserve carriers are extended and retained by a holder. In looms of the type mentioned, operation of the replenishing mechanism incidentally results in 10 the formation of outgoing and incoming filling ends projecting from the cloth selvage, which filling ends are cut adjacent the cloth selvage and thereupon become loose pieces of filling thread. Unless the loose pieces of thread are gathered and removed from the loom, they are 15 apt to be caught by the lay or shuttle and drawn into the cloth, thereby causing defects in the cloth.

In prior looms pneumatic means have been 20 provided to hold the ends of the filling thread of the reserve carriers and also pneumatic means have been provided to remove the loose pieces of filling ends away from the loom. In such prior structures the means for actuating and controlling the pneumatic means have been either too 25 costly or involved or both with the result that looms used commercially have not been provided with pneumatic means for holding the filling ends and removing the loose pieces of filling ends, to 30 any great extent.

A principal object of the present invention is to provide in an automatic replenishing loom having pneumatic means for holding and tensioning the filling thread and removing loose pieces of filling ends from the loom, electric means for operating the pneumatic means and novel means for supplying the electric energy for operating the electric means, which energy supplying 35 means shall be constructed and arranged to effect operation of the pneumatic means only at the time of and for an interval of several picks after each replenishing operation, whereby said pneumatic means shall be operated at the proper 40 time and for a sufficient length of time to effectively remove the loose pieces of filling ends and effectively hold and tension the filling threads of the reserve filling carriers in the magazine.

The foregoing and other objects of the present 45 invention are accomplished in the construction

illustrated on the accompanying drawings, of which:

Fig. 1 is a plan view of part of a loom having the preferred embodiment of my invention applied thereto;

Fig. 2 is a view in cross-section taken approximately on line 2—2 of Fig. 1, but to a larger scale;

Fig. 3 is a section view taken on line 3—3 of Fig. 4;

Fig. 4 is a view in cross section of the thermostatic switch taken approximately along line 4—4 of Fig. 3;

Fig. 5 is a view similar to Fig. 4, but showing the switch in a closed position;

Fig. 6 is a front view of the loom shown in Fig. 1;

Fig. 7 is a view in elevation of one corner of said loom;

Fig. 8 is a schematic wiring diagram of certain 20 electrical apparatus on said loom.

The loom shown on the drawings is but fragmentarily illustrated, the parts and mechanisms not shown being of any suitable usual construction and not of the present invention. 25 In addition, certain of the parts shown are not new, they being of the present invention only to the extent that they comprise parts that may be used as elements in the combination defined in 30 the appended claims.

The aforesaid old parts include a loom frame of which the right hand loom side 1 and breast beam 2 are shown, and also include the lay, reed, shuttle box, shuttle, picking mechanism and filling replenishing mechanism hereinafter 35 described. The lay includes a lay beam 3 mounted to reciprocate toward and from the front of the loom and carries a shuttle box 4 at one end thereof. The shuttle box 4 is located at the replenishing end of the lay, which in the present instance is at the right hand side of the loom.

A shuttle 5, carrying the filling supply, is picked from side to side of the loom along the lay beam 3, by picking mechanism, including a picker stick 6. As the shuttle is thus picked, it lays picks of filling thread in the shed S which filling thread is beaten into the fell by reed 7 to thereby form cloth C. The filling supply in the shuttle usually lasts for an interval of several 50 hundred or even several thousand picks, and when the supply is substantially exhausted a fresh supply is provided by automatic filling replenishing mechanism.

The automatic filling replenishing mechanism 55

shown includes a rotary hopper or magazine 8 having a supply of bobbins 9 therein, and also includes a transferrer 10 and means, of which a rod 11 is shown, for initiating operation of the 5 transferrer. When the filling supply in the shuttle is determined (by means not shown) to be substantially exhausted, the starting rod 11 is turned in a direction clockwise on Fig. 2. This moves other usual devices not shown, and when the 10 shuttle 5 enters the shuttle box 4 the transferrer 10 inserts a fresh bobbin 9 therein and expels the exhausted bobbin from the shuttle. The filling ends F of the filling on the bobbins 9 are extended 15 beyond the end of the magazine 8 and are held and tensioned by pneumatic holding and tensioning mechanism. Any suitable pneumatic holding and tensioning mechanism may be used, however the particular type preferred and disclosed 20 may be similar to that disclosed and claimed in my co-pending application Serial No. 305,153, filed Nov. 18, 1939.

The preferred type of filling end holding and tensioning mechanism includes a holding member, preferably in the form of a conduit 13 having 25 an opening 14 therein. The opening 14 may consist of the open end of the conduit 13. The opening 14 in the conduit is so located that it may receive or contain the ends of all of the filling ends F. Thus in the embodiment shown, the opening 30 14 is located above the shuttle box 4 adjacent the outer end of the magazine 8, but below and slightly back of the axis of rotation of the magazine.

The filling ends F, extended as above described, 35 are manually presented to or adjacent the opening 14 at the time when the bobbins 9 are inserted in the magazine. The loom is provided with means, hereinafter to be described, for inducing currents of air to flow into the opening 14 to thereby draw 40 the ends F into the holder or conduit 13.

Immediately after the replenishing operation, above described, is completed, the lay moves rearwardly and the shuttle 5 is picked along the lay beam 3 through the shed S, thereby laying a pick 45 of filling thread (from the fresh supply) in the shed. Then the lay beats this pick of filling into the cloth C thereby leaving an end f' of filling extending from the cloth selvage to the holder 13. This filling end f' is known in the art as the incoming filling end.

At the time of each transferring operation, the filling thread is parted between the ends of the shuttle, and the branch f of such thread, which projects from the cloth selvage is clamped and 55 withdrawn forwardly out of the shuttle box 4. The end f is known as the outgoing filling end. The drawings show parting and clamping blades 12 for parting, clamping and withdrawing the outgoing filling end f. The blades 12 and the mechanism therefor, not shown, may be substantially the 60 same as in patent to Stafford No. 1,552,388, granted Sept. 1, 1925, to which patent reference may be had for a more complete disclosure.

Both the incoming filling end f' and the outgoing filling end f are parted adjacent the cloth selvage by any suitable means such as the usual temple thread cutter 15. The thread cutter is operative to part the filling ends f and f' within a few picks after the replenishing operation is 70 completed. The parting of these filling ends forms the loose pieces of filling thread, above mentioned, which are apt to be drawn into the cloth.

Any suitable pneumatic means may be provided for gathering the loose pieces of filling 75 thread and removing them from the loom. The

particular type preferred and shown may be similar to that disclosed and claimed in my co-pending application Serial No. 304,095, filed Nov. 13, 1939.

In the particular embodiment shown, such pneumatic means includes a pipe or conduit 16, 5 supported by a bracket 17 so as to terminate directly in front of the shuttle box 4 intermediate the ends thereof, and beneath the magazine 8. When thus supported the open end 18 of conduit 16 is closely adjacent the outgoing filling end f. 10 Means are provided to induce a flow of air into conduit 16.

The particular pneumatic means shown for inducing a current of air to flow into conduits 13 and 16 includes a conduit 19 connected at its 15 upper end to conduits 13 and 16 and connected at its lower end to the intake of a rotary suction fan or pump 20 which is enclosed in a housing 21. The fan 20 is electrically operated, and to this end it may be fixed on the end of the rotor 20 shaft 22 of an electric motor 23. The housing of the motor 23 may be bolted directly to the housing 21 of the fan and the unit thus formed may be supported on a fixed bracket 24. The exhaust conduit 25 of the housing 21 may lead to any suitable point remote from the moving parts of the loom.

It will be apparent that when the motor 23 and fan 20 are in operation, all of the filling ends F within the opening 14 will be held and tensioned 30 simultaneously by the currents of air flowing into the opening. The yielding tension thus provided is particularly desirable during actual operation of the replenishing mechanism and during the first pick of the shuttle after each replenishing 35 operation. It is also desirable that the pneumatic means, such as fan 20, be in operation at the time when, after each replenishing operation, the incoming filling end f' is parted adjacent the cloth selvage by the temple thread cutter 15. With the 40 pneumatic means in operation as aforesaid, the parted incoming filling end f' is promptly carried through the conduit 13 and out the exhaust 25 45 and is thereby removed from the loom.

When the fan 20 is in operation during the 45 actual operation of the replenishing mechanism as aforesaid, the outgoing filling end f, upon being severed and clamped by the parting and cutting means 12 and withdrawn forwardly out of the shuttle box 4, will be sucked into the opening 18 50 of conduit 16 upon being released by the clamp. Upon the later severance of the outgoing filling end f adjacent the cloth selvage by the temple 55 thread cutter 15, the filling end will be promptly carried through the conduit 16 and out the exhaust 25 and thereby removed from the loom.

According to the present invention, the pneumatic means is to be operated intermittently. More specifically, means are provided which normally supply electric energy to the motor 23 60 only during and for an interval of a plurality of picks after each replenishing operation. The preferred means for this purpose includes an electric circuit of which one lead 26 is directly connected to the motor 23 and the other lead 27 is connected to a thermostatic switch 28, which in turn is connected to the motor 23 by a lead 29. When the switch 28 is closed, the circuit to the motor is complete and the motor, of course, then operates. 65

The particular thermostatic switch shown includes an insulating housing member having a base 30 and circular side walls 31. A stud 32 is threaded into the base 31 and extends upwardly within the housing, a disc-shaped bi-metallic thermostatic member 33 is fixedly secured to stud 70 75 32.

32 between collars 34 and 35 carried by the stud leaving this member free and unrestrained outside this confined central portion. The stud 32 carries a push button 36 at its upper end. The 5 push button 36 is slideable upon stud 32 and a spring 37 serves to hold the push button in its upper position.

Fixedly connected to push button 36 is a plate 37' carrying adjacent each outer end projections 10 38. The thermostatic member 33 has on its bottom surface adjacent the outer periphery thereof two contact points 39 and 40. Secured to the inner surface of the base 30 are three contact 15 points 41, 42 and 43. Contact points 41 and 42 carried by the base 30 are located directly beneath contact points 39 and 40 carried by the thermostatic member 33. The lead 27 is connected to contact point 41 and lead 29 is connected to contact point 42. A fine wire coil 44 located on the 20 inner surface of the base 30 and beneath the thermostatic member 33, connects contact point 42 with contact point 43. A resistance 45 is connected to contact point 43 and to lead 26.

The thermostatic member 33 is normally flexed 25 in the position shown in Fig. 4. The member 33 is capable of quickly passing to the opposite flexed position shown in Fig. 5, when pressure is exerted on push button 36 moving it inwardly and thereby causing projections 38 to press on the periphery 30 of member 33. Member 33 is also capable of quickly flexing back to the normal flexed position shown in Fig. 4, upon being heated to a critical 35 temperature. Thus member 33 is capable of quickly passing from a first to a second of two opposite flexed positions upon the application of external force and also capable of quickly passing back to the first position from the second position upon being heated to a critical temperature.

The contact points 39 and 40 carried by member 40 33 are held spaced apart from the contact points 41 and 42 when member 33 is in the first or normal position as shown in Fig. 4. Upon movement of member 33 to the second position by pressure upon 45 push button 36 contact points 39 and 40 are brought and held in contact with contact points 41 and 42.

Means are provided for pushing the push button 36 inwardly, thereby closing the electric 50 circuit and supplying energy to motor 23. The particular means shown include a lever 46 loosely pivoted upon rod 11. The rear end of lever 46 has an upturned projection 47 to contact the push button 36 and the forward end of lever 46 provides a handle for manual operation of the lever. 55 The bottom of lever 46 rests on a projection 48 on the shuttle feeler starting arm 49 which is fixedly connected to rod 11 to turn therewith. Upon the turning of rod 11 in a clockwise direction, as seen in Fig. 2, to call for operation of the replenishing 60 mechanism, arm 49 with the projection 48 is raised, thereby raising lever 46 causing the projection 47 to push on the push button 36.

The operation of the device is as follows:

Upon rod 11 turning to call for operation of 65 the replenishing mechanism lever 46 pushes on the push button 36, causing the thermostatic member 33 to quickly pass from the position shown in Fig. 4 to that shown in Fig. 5 thereby making contact between contact points 39 and 40 70 and 41 and 42 respectively, closing the circuit and causing the motor 23 to operate the fan. Immediately upon the circuit being closed, electricity flows into coil 44 causing it to heat up and thereby heat the thermostatic member 33 to the critical 75 temperature, which upon being reached causes

member 33 to quickly pass to the position shown in Fig. 4 thereby breaking contact between contact points 39 and 40 and 41 and 42 respectively and opening the circuit thereby stopping the motor and fan. The rate of heating of the coil 44 may 5 be varied and controlled by changing the resistance 45, and the rate of heating will be so set as to raise the temperature of the member 33 to the critical temperature a predetermined interval from the closing of the circuit by the operation 10 of the rod 11.

The switch 28 is attached to a bracket 50 which in turn is fixed to the loom frame so located as shown in Figs. 1 and 2 as to be in position to be contacted by the projection 47 on lever 46.

If considered desirable the conduit 13 may be lined with a friction material 51, extending inwardly a short distance from the opening 14. Such friction material may consist of pile fabric or fur or the like and provides holding means during 20 the period of non-operation of the pneumatic means.

Having fully disclosed the preferred embodiment of my invention, I claim:

1. In an automatic filling replenishing loom of 25 the type incidentally forming loose pieces of filling ends, said loom having filling replenishing mechanism including a magazine adapted to hold a multiplicity of reserve filling carriers having filling ends projecting therefrom, the combination of 30 electrically operated pneumatic means for holding and tensioning said filling ends and for removing said loose pieces of filling ends, and an electric circuit supplying electric energy to said electrically operated pneumatic means, said circuit including a thermostatic switch, mechanical means for closing said switch each time said replenishing mechanism operates and automatic electrically operated means in said circuit arranged to effect the opening of said switch a 35 plurality of picks after each replenishing 40 operation.

2. In an automatic filling replenishing loom of 45 the type incidentally forming loose pieces of filling ends, said loom having filling replenishing mechanism including a magazine adapted to hold a multiplicity of reserve filling carriers having filling ends projecting therefrom, the combination of 50 electrically operated pneumatic means for holding and tensioning said filling ends and for removing said loose pieces of filling ends, an electric circuit supplying electric energy to operate said pneumatic means, and a switch for closing and opening said circuit, said switch comprising a thermostatic member movable to close and 55 open said circuit, mechanical means operable by a moving part of the loom on operation of said replenishing mechanism to move said member to close said circuit and means set in operation upon closure of said circuit to move said member to open said circuit at a later predetermined 60 interval.

3. In an automatic filling replenishing loom the 65 combination of pneumatic filling end holding and tensioning means, pneumatic filling end removing means, electrical means for operating said pneumatic means and thermostatic means for controlling the operation of said electrical means, said thermostatic means comprising a member capable of passing from one to the other 70 of two opposite flexed positions under the influence of heat, said member in one of said positions permitting the flow of electric energy to said electrical means, and in the other of said positions stopping the flow of electric energy to 75

said electrical means; mechanical means for moving said member to the position permitting the flow of electric energy operable upon each operation of said replenishing mechanism, and automatic means for heating said member after each replenishing operation to thereby cause said member to move to the position for stopping the flow of electric energy to said electrical means a predetermined interval after each said replenishing operation.

4. A loom having a reciprocating lay, an automatic filling replenishing mechanism, a pneumatic filling end remover and filling end holder for holding the reserve filling ends and for 15 moving the loose pieces of incoming and outgoing filling ends, an electric motor for operating said remover and holder, and means controlling the supply of electric energy to said motor, said means comprising an electric circuit having spaced contact points providing a normally open circuit, a 20 thermostatic contact making member capable of passing from a first to a second of two opposite flexed positions upon the application of external force and also capable of passing back to said 25 first position upon being heated to a critical temperature, said member when in said first position being spaced from said contact points and when in said second position contacting said points and thereby closing said circuit, mechanical 30 means actuated upon each replenishing operation to move said member to said second position, and means operable after the operation of said replenishing mechanism to heat said member to said critical temperature after a predetermined interval, thereby causing said member 35 to move back to said first position and open said circuit.

5. A loom having a reciprocating lay, automatic filling replenishing mechanism, including a 40 magazine adapted to hold a multiplicity of reserve filling carriers, said carriers having filling ends projecting therefrom, electrically operated pneumatic means for holding and tensioning said filling ends, an electric circuit supplying electric 45 energy to operate said pneumatic means, said circuit including a thermostatic switch, mechanical means for closing said switch each time said replenishing mechanism operates and automatic electrically operated means in said circuit arranged to effect the opening of said switch a plurality of picks after each replenishing operation.

6. A loom having a reciprocating lay, automatic filling replenishing mechanism including a 55 magazine adapted to hold a multiplicity of reserve filling carriers, said carriers having filling ends projecting therefrom, pneumatic means for holding and tensioning said filling ends, a motor for operating said pneumatic means, an electric circuit supplying electric energy to said motor said 60 circuit including a thermostatic switch, said switch comprising a member mechanically movable to a position permitting the flow of electric energy to said motor and thermostatically movable to a position stopping the flow of electric energy to said motor, mechanical means actuated upon each replenishing operation to move said member to said first named position and means for heating said member to thereby cause said member to move to said second named position a plurality of picks after each replenishing operation.

7. A loom having a reciprocating lay, an automatic filling replenishing mechanism, a pneumatic filling end holder, an electric motor for 75 operating said holder and means controlling the

supply of electric energy to said motor; said means comprising an electric circuit having spaced contact points providing a normally open circuit, a thermostatic contact making member capable of passing from a first to a second of two opposite flexed positions upon the application of external force, and also capable of passing back to said first position upon being heated to a critical temperature, said member when in said first position being spaced from said contact points and when in said second position contacting said points and thereby closing said circuit, mechanical means actuated upon each replenishing operation to move said member to said second position, and means operable after the operation of said replenishing mechanism to heat said member to said critical temperature, thereby causing said member to move back to said first position and open said circuit.

8. A loom having a reciprocating lay, automatic filling replenishing mechanism incidentally forming the usual outgoing and incoming filling ends projecting from the cloth selvage, means for parting said filling ends adjacent the cloth selvage, pneumatic means constructed and arranged to gather the parted filling ends and remove them from the loom, an electric motor for operating said pneumatic means, an electric circuit supplying electric energy to said motor, said circuit including a thermostatic switch, mechanical means for closing said switch at the time of each operation of said replenishing mechanism, and electrically operated means in said circuit arranged to effect the opening of said switch a plurality of picks after each replenishing operation.

9. A loom having automatic filling replenishing mechanism which incidentally forms the usual outgoing and incoming filling ends projecting from the cloth selvage, means for parting said filling ends adjacent the cloth selvage, electrically operated pneumatic means for gathering the parted filling ends and removing them from the loom and means supplying electric energy to said electrically operated means only during and for a predetermined interval after each operation of said replenishing mechanism, said energy supplying means comprising a member mechanically movable to a position permitting the flow of electric energy to said electrically operated means and thermostatically movable to a position stopping the flow of electric energy to said electrically operated means, mechanical means actuated upon each replenishing operation to move said member to said first named position and means for heating said member to thereby cause said member to move to said second named position a plurality of picks after each replenishing operation.

10. A loom having a reciprocating lay, an automatic filling replenishing mechanism, a pneumatic filling end remover, an electric motor for operating said remover and means controlling the supply of electric energy to said motor, said means comprising an electric circuit having spaced contact points providing a normally open circuit, a thermostatic contact making member capable of passing from a first to a second of two opposite flexed positions upon the application of external force and also capable of passing back to said first position upon being heated to a critical temperature, said member when in said first position being spaced from said contact points and when in said second position contacting said points and thereby closing said circuit, mechanical means actuated upon each replenishing operation to move

5 said member to said second position and means operable a predetermined interval after the operation of said replenishing mechanism to heat said member to said critical temperature, thereby causing said member to move back to said first position and open said circuit.

11. A loom having a reciprocating lay, automatic filling replenishing mechanism, an electrically operated pneumatic filling end remover 10 and means for controlling the supply of electric energy thereto, said means comprising a thermostatic member capable of passing from a first to a second of two opposite flexed positions upon application of external force and also capable of 15 passing back to said first position upon being

heated to a critical temperature, said member when in said first position stopping the flow of electric energy to said electrically operated pneumatic filling end remover and when in said second position permitting the flow of electric energy to 5 said remover, mechanical means actuated upon each operation of said replenishing mechanism for moving said member to said second position and means operable a predetermined interval after the operation of said replenishing mechanism 10 to heat said member to said critical temperature whereby said member moves to said first position thereby stopping the flow of electric energy to said remover.

CARL D. BROWN. 15
